UNITED STATES PATENT OFFICE.

LOUIS R. KRUG, OF ALBANY, NEW YORK, ASSIGNOR TO BURDICK & SON, OF ALBANY, NEW YORK.

MOLDING DEVICE.

1,221,459.

Specification of Letters Patent. Patented Apr. 3, 1917.

Application filed February 8, 1917. Serial No. 147,375.

To all whom it may concern:

Be it known that I, LOUIS R. KRUG, a citizen of the United States of America, residing at the city of Albany, in the county 5 of Albany and State of New York, have invented certain new and useful Improvements in Molding Devices, of which the following is a specification.

My invention relates to molding devices, 10 and the object of my invention is to provide a countersunk hinged tube adapted to be formed into a casting during the casting process; together with such other elements and combinations as are hereinafter 15 more particularly set forth.

I accomplish these objects by means of the mechanism illustrated in the accompanying drawing, in which:

Figure 1 is a perspective view of a pattern. 20

Fig. 2 is a perspective view of a casting.

Fig. 3 is a perspective view of my countersunk hinged tube.

Fig. 4 is a section along the line, X—X, 25 on Fig. 3, when sand has been placed in the tube.

Fig. 5 is a plan of the hinged plate when opened or before being bent.

Fig. 6 is an elevation of the tube before it 30 is placed in the plate.

Similar letters refer to similar parts throughout the several views.

It is often desirable to have the heads of bolts, screws or rivets, especially in stoves, 35 countersunk, and in order to accomplish this it is usually necessary to drill and countersink the casting after it is made so as to make an opening or hole in the casting and enlarge it, so that the head of the bolt, 40 screw or rivet may pass through it and be caused to assume a position flush with the surface of the casting. In order to do away with this drilling and countersinking work, I have provided a very effective, economical 45 and simple hinged tube which may be inserted in the pattern and become a part of the casting, and the countersunk tube will become in the casting a countersunk passageway for the bolt, screw or rivet.

50 Referring to the drawing: I show in Fig. 5 a thin tin plate, A, with an enlarged opening, B, near one end and a smaller opening, C, near the other end. I bend this plate along a line between the openings, as

at D, causing the bent portion to extend substantially at right angles to the remaining portion, and then I bend the plate again along the line, E, causing the opening, B, to assume a position above the opening, C, and the two parts of the bent-over plate to be separated from each other by the portion, F, as shown in Fig. 3. A tube, G, having a cup-shaped flange, g, forming a countersunk opening, H, is placed through the opening, B, the sides of said opening, B, 65 engaging and secured to the sides of the flange, g; and the smaller portion of the tube, G, engaging and secured to the smaller opening, C, as shown in Figs. 3 and 4. When the tube is in position in the plate 70 as shown in Fig. 3, it is inserted in the slot, J, in the pattern, K, where it may be held in place by having the sides of the plate enter the grooves, L, along the sides of the slot, J. I do not limit myself to this 75 holding means.

Sand is placed in the tube, G, filling the cup-shaped or countersunk portion, H, as shown in Fig. 4, and when the pattern with the countersunk hinged tube in it is placed 80 in the sand and after the pattern has been removed leaving the hinged tube in the sand and the iron is poured, it fills up the spaces between the two separated portions, a and b, of the plate, A; and when the casting is removed from the sand it will be in the form 85 shown in Fig. 2 with the countersunk opening in the tube, the tin plate A, forming a part of the casting.

What I claim as my invention and desire 90 to secure by Letters Patent is:

1. A countersunk hinged tube, comprising a metallic plate bent upon itself, forming two portions slightly separated from each other; a tube having one end in an 95 opening in one of the portions of said plate; an enlarged, flaring cup-shaped flange portion formed at the other end of said tube secured in an opening in the other portion of said plate; and a pattern provided with 100 an opening into which said plate carrying said tube may be inserted and held during the molding process.

2. A thin metallic plate provided with an enlarged opening near one end and a smaller opening near the other end; said plate bent at right angles along a line between said openings and then bent along a line a short 105

distance removed from the first mentioned line to such a position that the two major portions of the plate will be located one above and slightly removed from the other; 5 a tube having a flaring cup-shaped enlarged portion at one end adapted to fit in the larger of said openings in the plate, the other end of said tube adapted to fit into the

smaller of said openings, all substantially as described.

10

In testimony whereof I have affixed my signature in the presence of two witnesses.

LOUIS R. KRUG.

Witnesses:

FREDERICK W. CAMERON,
BEULAH CARLE.
